CLAIM

I claim the ornamental design for utensil storage set, as shown and described.

DESCRIPTION

FIG. 1 is a prospective view of utensil storage set showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown in the figures depict portions of the utensil storage set that form no part of the claimed design.

1 Claim, 5 Drawing Sheets
